EXTENDED COUPLING FOR A TRAILER

David H. Hill, Ramsey, and Robert A. Marquardt,
Lebanon, Ill., assignors to Tri-Star Corporation, Fill-
more, Ill.

Filed Nov. 1, 1973, Ser. No. 411,669

Term of patent 14 years

Int. Cl. D12—16

U.S. Cl. D12—162

FIG. 1

FIG. 4

FIG. 5

FIG. 6

FIG. 2

FIG. 3

FIG. 1 is a perspective view of an extended coupling for a trailer showing our new design;
FIG. 2 is a side elevational view thereof;
FIG. 3 is a top plan view thereof;
FIG. 4 is a front elevational view thereof;
FIG. 5 is a rear elevational view thereof; and
FIG. 6 is a bottom plan view thereof.

The broken lines in the drawing are for illustrative purposes only.

We claim:

The ornamental design for an extended coupling for a trailer, substantially as shown and described.
